CARBURETING DEVICE

Marcel Louis Mennesson, Neuilly-sur-Seine,
France, assignor to Societe Solex, a society of
the Republic of France

Application February 27, 1946, Serial No. 650,517
In France February 8, 1945

Section 1, Public Law 690, August 8, 1946
Patent expires February 8, 1965

2 Claims. (Cl. 261—41)

1

The present invention relates to carburetting devices including an auxiliary carburetter for facilitating the starting from cold of internal combustion engines, said auxiliary carburetter being of the kind of those described in French Patents No. 700,188 and 751,064, filed by Société Anonyme Solex. Such auxiliary carburetters essentially include a well communicating through a calibrated orifice with the constant level chamber below the fuel level, and fed with air at its upper part, the fuel mixture thus obtained being mixed with air, and the whole being fed, through a passage controlled by a cock, to the engine intake pipe on the downstream side of its throttle valve.

The chief object of my invention is to provide a device of this kind which is better adapted to meet the requirements of practice than those made up to this time, in particular concerning the feed of air to the air intakes of the auxiliary carburetter and the fluidtightness of the cock that serves to bring the auxiliary carburetter into or out of action and to adjust the section of the passage through which the fuel mixture is fed to the engine intake.

According to a feature of the present invention, the air intakes in question and in particular the upper end of the well are connected, not with the atmosphere but with the space of the constant level chamber above the fuel, said space being itself connected, through an orifice of large section, with the main air inlet—generally fitted with a purifier or filter—of the main carburetter, so that the air intakes of the auxiliary carburetter are fed through the air intake of the main carburetter and any slight depression as may be produced in the well of the auxiliary carburetter, when the latter is brought into play, remains practically without influence on the pressure existing in the constant level chamber.

According to another feature of the present invention, there is provided, between the parts of the channel for the feed of the fuel mixture from the auxiliary carburetter that are respectively located on the upstream side and the downstream side of the above mentioned cock, a chamber in communication either with the atmosphere, or with the air intake of the main carburetter or again with the constant level chamber above the normal fuel level therein, in order to prevent the depression, existing in the downstream part, from being transmitted to the upstream part due to a lack of fluidtightness of said cock.

Fig. 1 shows, in diagrammatic axial section, a

carburetting device made according to the invention;

Fig. 2 shows, in a similar way, a portion of the same device, but with parts thereof occupying another position;

Fig. 3 is a view, similar to Fig. 2, showing a modification.

The main carburetter is constituted in any suitable manner, in particular as usual. Fig. 1 shows, by way of example, only some essential elements of an inverted type carburetter, i. e. a body 1, an air intake 2 (generally provided with a purifier or filter), a venturi 3, a jet device 4 (shown in external view), a throttle valve or butterfly valve 5, and a constant level chamber 6 with its float 7.

Concerning the auxiliary carburetter it is essentially constituted, as indicated in French Patents No. 700,188 and 738,525 filed by Société Anonyme Solex. In the example illustrated by the drawings, it includes a well 9 fed with fuel, at its lower part, through a calibrated orifice 10 opening into the constant level chamber 6 below the fuel level therein. A conduit 11 starting from a point of well 9 located at a given distance below the fuel level leads, through a channel 12, to a distributing device including a chamber 13 and a plate or disc 14, of generally circular shape, adapted to be rotated by means of a spindle 15 and an eternal control member 16. Said plate is applied on its seat, constituted for instance by a plane portion of the body 1 of the carburetter, by a spring 17 so as to form a fluidtight partition between channel 12 and chamber 13 when the cock is closed (Fig. 2).

When the cock is open (Fig. 1) for bringing the auxiliary carburetter into action, an orifice 18 provided in plate 14, is in registry with the opening of channel 12 and permits the contents thereof to pass into chamber 13. At the same time another orifice 19 of plate 14 comes opposite a passage 20 opening into the intake pipe of the engine, on the downstream side of throttle valve 5, and therefore in direct communication with the engine. Chamber 13 is permanently connected, through calibrated orifice 22, with a conduit 21 which communicates at 23 with the air intake 2 of the main carburetter. Under these conditions the depression from the engine is transmitted to chamber 13 through passage 20 and sucks in, on the one hand the air supplied through conduit 21, and calibrated orifice 22 and, on the other hand, the fuel mixture delivered through channel 12 and conduit 11 from well 9.

In the above mentioned prior patents, the upper part of well 9 was connected directly with the atmosphere or with the air intake of the main carburetter.

According to the present invention, the upper part of the well communicates, at 24, with the constant level chamber 6—above the normal level of the fuel contained in this chamber—and, consequently, with the air intake of the main carburetter through orifice 8.

As the transverse section of well 9 is large in comparison with that of conduit 11, calibrated orifice 10 is subjected but to a small portion of the depression that exists in said conduit 11, and its output is substantially constant. It follows that the fuel mixture becomes leaner and leaner as the speed of the engine increases. However, in order to have an operation that is quite correct, the free surfaces of the liquid, in well 9 and in the constant level chamber must be exactly at the same pressure, otherwise a slight difference of pressure would cause the fuel to rise or to drop in well 9 thus producing perturbances that are often very serious.

The only way to obtain this result is to cause the upper part of well 9 to open into the constant level chamber itself, this chamber being in communication with the main air intake 2 through an orifice 8 of sufficiently large size. As a matter of fact, if orifice 8 is too small, conduit 11 creates a slight depression in constant level chamber 6, which has for its effect to cause a drop of level in the main jet system 4 and to make it difficult for gasoline to spout out from this system when butterfly valve 5 is gradually opened for increasing the power of the engine. It is therefore important that the depression existing in conduit 11 when starting should produce no depression in constant level chamber 6. It is therefore necessary to give orifice 8 a sufficiently large section. On the other hand conduit 11 has a portion thereof located at a sufficiently high level for avoiding a constant flow of fuel toward plate 14.

When the auxiliary carburetter is started into operation, there might take place a siphoning of the fuel through conduit 11, channel 12 and orifice 18 when the latter is open or even through an eventual leak between plate 14 and its seat if orifice 18 is not opposite the channel 12. In order to avoid such a siphoning, a hole 25 is provided at the top point of conduit 11. On the other hand, when the auxiliary carburetter is out of action, orifice 19 is no longer opposite passage 20 and orifice 18 is no longer opposite the opening of channel 20.

It was proposed, in the prior patents above mentioned, to provide—when the auxiliary carburetter is out of action—a second orifice, analogous to that designated by 18, for causing atmospheric pressure to act in conduit 11. In the case of the device that constitutes the object of the present invention, such a hole would connect channel 12 with chamber 13 and, consequently, with the main air intake of the carburetter through conduit 21 and orifice 23. Now, there may exist a difference of pressure between the orifice 23 and the orifice 8 which would have for its effect, either to drive fuel toward chamber 13, or, on the contrary, to cause air to enter well 9, this air then passing through conduits 21, 12 and 11.

In order to avoid these drawbacks, any communication should be cut off, when the auxiliary carburetter is out of action (Fig. 2), between

channel 12 and chamber 13. But it may happen, due to a lack of fluid tightness, that the depression from the engine intake pipe is transmitted through passage 20 to channel 12 by passing between plate 14 and its seat, which would have for its effect to suck out fuel from well 9, this fuel then passing directly into the suction pipe of the engine.

This is remedied by surrounding the outlet of channel 12 by a groove 26 communicating, for instance, with the outside. With such an arrangement, a slight depression tending to reach channel 12 through the interval that may exist between plate 14 and its seat would first meet with this groove 26 and the only inconvenience that might result therefrom would be that the engine would suck in a small amount of air through the leak thus formed.

However, there may also exist a slight lack of fluidtightness between groove 26 and channel 12 due to a defective contact between plate 14 and its seat and, in these conditions, as constant level chamber 6 may be at a pressure lower than atmospheric pressure, air from the outside would enter conduit 11 through channel 12 and groove 26 and bubble in well 9, thus causing perturbations therein. It is therefore of interest to place groove 26 in communication through a conduit 27 with the part of constant level chamber 6 above the normal fuel level therein. In this way no difference of pressure can occur, when the auxiliary carburetter is out of action (Fig. 2), between channel 12 and groove 26, the latter remaining quite as efficient for compensating the effects of a certain suction transmitted from passage 20.

Another solution, shown by Fig. 3, consists in placing groove 26 in communication, through passage 28, with chamber 13. When the auxiliary carburetter is out of action (Fig. 3) passage 28 communicates directly with the carburetter air intake through chamber 13, calibrated orifice 22 and conduit 21.

This might also involve the drawback that a difference of pressure may exist between conduits 11 and 12 on the one hand, which are at the pressure of constant level chamber 6, and groove 26 on the other hand which is at the pressure existing in the carburetter air intake, at the inlet 23 of conduit 21.

This slight difference of pressure might produce a circulation of fuel through conduits 21, 12 and 11, but this can be remedied, as in the preceding case, by having recourse to a hole 25 (Fig. 5) which permits an inflow of air into conduits 11 and 12 preventing fuel from being sucked up to the top point of conduit 11 from which it could pass into channel 12. However the size of hole 25 is chosen such that it does not interfere with the suction of the fuel when plate 14 occupies a position for which the auxiliary carburetter is in action (Fig. 2), that is to say when the maximum depression exists in conduit 11.

Of course, the air that feeds calibrated orifice 22 might also be taken from constant level chamber 6 but as this orifice is, on the one hand and in general, of rather important dimension and, on the other hand, subjected to a strong suction, this arrangement would lead to an orifice 8 of considerable section. It is therefore preferable to have conduit 21 opening, at 23, into the main air intake of the carburetter and not into the constant level chamber.

In this carburation device, including a starting auxiliary carburetter, all the possible air in-

takes finally lead to the main air intake of the carburetter and are, consequently, fed with air filtered by the main filter of the carburetter, if such a filter exists, without having to fear that the feeds of these different air intakes, including that of the constant level chamber, give rise, during the working of the engine, to local pressure differences which might be the cause of disturbances in the working of the auxiliary carburetter or even in that of the constant level chamber.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the accompanying claims.

What I claim is:

1. A carburation device for an internal combustion engine which comprises, in combination, a main carburetter including an air intake, a constant level chamber communicating with said air intake through a large section passage, an induction pipe to be connected with said engine, and a throttle valve in said pipe, and an auxiliary carburetter for starting the engine from cold including a well provided with a calibrated orifice opening into said constant level chamber below the fuel level therein and with only one air inlet in direct communication exclusively with the space of said constant level chamber above the fuel level therein, a chamber located below said first mentioned chamber, a conduit starting from said well at a point thereof located below the fuel level in said constant level chamber, passing above said level and opening into one wall of said second mentioned chamber, a conduit starting from said induction pipe on the downstream side of said throttle valve and opening into said wall of the last mentioned chamber, a valve member slideable along said wall adapted either to connect both of said conduits with said last mentioned chamber or to cut off both of them therefrom, a conduit provided with a calibrated orifice for connecting said last mentioned chamber with said air intake, said wall of said last mentioned chamber being provided with an annular groove surrounding the opening of the first mentioned conduit into said wall, and means for connecting said groove with said second mentioned chamber.

2. A carburation device for an internal combustion engine which comprises, in combination, a main carburetter including an air intake, a constant level chamber communicating with said air intake through a large section passage, an induction pipe to be connected with said engine, and a throttle valve in said pipe, and an auxiliary carburetter for starting the engine from cold including a well provided with a calibrated orifice opening into said constant level chamber below the fuel level therein and with only one air inlet in direct communication exclusively with the space of said constant level chamber above the fuel level therein, a chamber located below said first mentioned chamber, a conduit starting from said well at a point thereof located below the fuel level in said constant level chamber, passing above said level and opening into one wall of said second mentioned chamber, the upper portion of said conduit being provided with an orifice of small section connecting it with the space of said constant level chamber located above the fuel level therein, a conduit starting from said induction pipe on the downstream side of said throttle valve and opening into said wall of the last mentioned chamber, a valve member slideable along said wall adapted either to connect both of said conduits with said last mentioned chamber or to cut off both of them therefrom, a conduit provided with a calibrated orifice for connecting said last mentioned chamber with said air intake, said wall of said last mentioned chamber being provided with an annular groove surrounding the opening of the first mentioned conduit into said wall, and means for connecting said groove with said second mentioned chamber.
